Max Mayerson, Richmond Heights, Mo.

Application June 18, 1947, Serial No. 139,780

Term of patent 3½ years

(Cl. D56—4)

To all whom it may concern:

Be it known that I, Max Mayerson, a citizen of the United States, residing at the city of Richmond Heights, in the county of St. Louis and State of Missouri, have invented a new, original, and ornamental Design for a Phonograph, of which the following is a specification, reference being made to the accompanying drawing, forming part thereof.

In the accompanying drawing:

Figure 1 is a perspective view of a phonograph, showing my new design, with the door of said phonograph closed.

Figure 2 is a top plan view thereof, with the door open.

Figure 3 is a side view thereof, with the door open.

Figure 4 is a front elevation thereof, with the door open.

I claim:

The ornamental design for a phonograph, as shown.

MAX MAYERSON.
